RAILWAY TRUCK

Robert B. Cottrell, Chicago, Ill., assignor to
 American Steel Foundries, Chicago, Ill., a corporation of New Jersey

Application May 12, 1941, Serial No. 393,000

22 Claims. (Cl. 105—197.2)

My invention relates to a railway car truck and especially to a quick wheel change form of truck wherein the bolster is readily dismantled from either side frame in order to permit the application of new wheels.

The general object of my invention is to devise a novel form of truck squaring means peculiarly adaptable to a quick wheel change truck and comprising means readily dismantlable when it is desired to change wheels.

A specific object of my invention is to devise a novel form of tie between the side frame and each end of the bolster which will permit normal play therebetween but will serve to restrain the bolster against the abnormal movements such as might cause unusual wear at the columns or tend to result in out-of-squareness of the truck parts.

My invention comprehends an arrangement wherein means is associated with the bolster projecting outboard each side frame with which may be resiliently associated a control bar, the opposite ends of said bar extending inboard for resilient connection to the adjacent side frame centrally of each column.

In my novel arrangement, the side frames are of the usual truss type and the columns are of well-known form, but in each column the inboard flange is extended in order to accommodate the before-mentioned connection to the stabilizing or control bar. As shown, my novel car truck comprises spaced side frames and a connecting bolster and associated with each bolster end is an interlocking member of well-known form serving to tie said bolster end to the associated side frame.

My present invention contemplates an arrangement of the bolster and interlocking member which will facilitate connection thereto of such a control bar as I have already mentioned. In one embodiment, the control bar may be connected between projecting portions of the interlocking member and bolster. In another embodiment, the control bar may be resiliently connected to the interlocking member.

Figure 1 is a fragmentary side elevation of a railway car truck embodying my invention.

Figure 2 is a sectional view therethrough, the section being taken substantially in the transverse vertical plane bisecting the truck with the central portion of the bolster being shown in elevation.

Figure 3 is a fragmentary top plan view of the truck structure shown in Figures 1 and 2. In each of Figures 1 to 3, only one side of the truck structure is shown inasmuch as the arrangement is similar at opposite sides thereof.

Figure 4 is a sectional view enlarged through the control bar and bolster connection substantially in the transverse vertical plane indicated by the line 4—4 of Figure 1.

5 Figure 5 is a further sectional view taken through the connection of the control bar to the side frame, said section being taken substantially in the transverse vertical planes indicated by the line 5—5 of Figure 1.

10 Figures 6, 7, and 8 show a modified form in which the control bar is connected to the bolster end in somewhat different manner, Figure 6 being a fragmentary top plan view of said connecting arrangement, Figure 7 a fragmentary view in elevation, and Figure 8 a sectional view taken substantially in the vertical transverse plane bisecting the bolster end as indicated by the line 8—8 of Figure 7.

15 Describing the structure in detail, my novel side frame is of well-known truss type comprising the compression member 2, the tension member 4, and the integral column 6 forming therewith a central bolster opening 8, said compression member over said bolster opening having the box-section illustrated in Figure 2 and said tension member, likewise, having a box-section beneath said bolster opening with the top chord 10, the bottom chord 12, the inboard wall 14, the outboard wall 16, and the intermediate wall 18, said

20 top chord 10 being widened and formed with upstanding inboard and outboard flanges 20 and 22 defining a spring seat 24. The spring seat 24 is cored away on opposite sides thereof as indicated at 26, 26 in order to accommodate the escape of

25 extraneous matter. On said spring seat may be supported a group of springs diagrammatically indicated at 28, 28, said spring group having a top spring plate 30 with openings to accommodate as at 32, 32 downwardly projecting position-

30 means on the end of the bolster 34. The general form of connection of the end of the bolster 34 in the bolster opening 8 is of well-known type, said bolster end having a widened top portion, the lateral shelves of which have a well-known con-

35 figuration best seen at 36 in the top plan view of Figure 3, said configuration comprising a generally convex form with a central slot in which may be received a central vertical flange on the adjacent column, said column thus being complementary in form to the adjacent wall of said shelf. Below the widened shelf portion at the side of the

40 bolster is conveniently positioned the upstanding end portion of the interlocking member generally designated 38, said interlocking member comprising a central plate portion transversely received

45 50 55

in the bottom wall of the bolster in the manner best seen from a consideration of Figures 2 and 3, said plate portion having a central boss 40 which extends through the bottom wall 42 of the bolster and is accommodated by a cored opening through the center wall 44.

In the present modification, each upstanding end portion of the interlocking member 38 is extended outboard the side frame in a jaw-like projection 46, said projection taking the form of a housing with a cylindrical bottom wall, vertical side walls, and end walls slotted as at 48 (Figure 4) to accommodate the extension therethrough of the control bar 50. In said housing 46 may be received the resilient member 52 of spool-like form, and said resilient member may be secured around said control bar in any convenient manner as by vulcanizing thereon prior to the assembly of the parts. The inboard wall of the housing 46 is extended upwardly and turned in to form the lip 54 (Figure 4) under which may project the edge 56 of the securing plate 58 which may be held in position by the threaded bolt 60, said threaded bolt extending through the housing 46.

The control bar 50 of U-like form as best seen in the top plan view of Figure 3 has a straight central portion which extends across the end of the bolster and is received in the jaws 46, 46 at opposite corners thereof, said bar also having the end portions arranged approximately at ninety degree angles to the central portion, each end portion being turned in an inboard direction and extending past the outboard flange of the adjacent column for connection as at 62 to the inboard flange 64 of the column, the form of said connection being shown in detail in Figure 5. It may be noted that said inboard flange is materially widened in order to accommodate this particular form of connection. In the detail of Figure 5, it may be noted that the end portion of the control bar 50 is formed with an abutment flange 66 against which may seat a washer 68, and between said washer and the column wall 64 may be compressed a resilient bushing 70. At the opposite side of the wall 64 may be positioned a similar bushing 70 compressed between said wall 64 and the washer 72 which is held in position by means of the securing nut 74 threaded on the end of the bar 50.

By my novel form of connection, each bolster end is permitted normal vertical movement on the supporting spring group and some slight lateral play is permitted by virtue of the resilient connection of the control bar to the side frame. The control bar, however, effectively restrains the bolster end against any excessive lateral movement or against any tipping tendency and, at the same time, serves to dampen somewhat any unusual vertical oscillations. Vertical movement of the bolster is permitted by distortion of the resilient connections at the ends of the control bar as well as by distortion of the rubber pads in the clamping means.

In the modified arrangement illustrated in Figures 6, 7, and 8, each end portion 102 of the bolster is continued in an outboard direction at each corner in an extension 104 with a downwardly opening cavity 106, and the bolster interlocking member 108 recessed in the bottom wall of the bolster in the usual manner as at 110 and interlocked therewith as at 112 is also formed with an outboard extension 114 at each corner thereof, said extension having an upwardly directed cavity 116 matching the before-mentioned cavity 106 and thus forming therebetween a recess with-

in which may be received the resilient spool or pad 118 which surrounds the control bar 120 and may be vulcanized thereto or simply slipped thereover into position. Said resilient pad or spool 118 is thus clamped between the members 104 and 114 at opposite corners of each bolster end. The end portions of the bar may be secured to the side frame column 122 in the manner described for the previous modification, and the end of the bolster 102 may cooperate with the column 122 in like manner as the previous modification and as seen at 124 in Figure 6.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a railway car truck, a truss side frame having a tension member, a compression member, and integral columns forming therewith a bolster opening and spaced window openings, a spring group on said tension member in said opening, a bolster end extending into said opening and seated on said spring group in guiding engagement with said columns, an interlocking member recessed in the bottom wall of said bolster and having guiding engagement with said columns, said interlocking member having means projecting outboard each column, a control bar connected to said means, said bar having end portions turned inboard, and means connecting said ends to said columns and resiliently controlling lateral, longitudinal and vertical movement of said bolster end.
2. In a railway car truck, a truss side frame having a tension member, a compression member, and integral columns forming therewith a bolster opening and spaced window openings, a spring group on said tension member in said opening, a bolster end extending into said opening and seated on said spring group in guiding engagement with said columns, an interlocking member recessed in the bottom wall of said bolster and having guiding engagement with said columns, said interlocking member having means projecting outboard each column, a control bar connected between said means and having end portions turned inboard, and means resiliently securing each of said end portions to the adjacent column, said means comprising resilient pads secured to said column and a connection between said portion and said pads.
3. In a four wheel truck, a truss side frame having top and bottom members and spaced columns defining a central bolster opening and spaced window openings, each of said columns having a transverse web and inboard and outboard flanges, a bolster end extending into said bolster opening with a widened top portion in guiding engagement with said columns, an interlocking member associated with said bolster end and also interlocked with said columns, clamping means on said interlocking member outboard of said frame, and a control bar resiliently secured in said clamping means and extending into said window openings for connection to said inboard flanges.
4. In a four wheel truck, a truss side frame having top and bottom members and spaced columns defining a central bolster opening and spaced window openings, a bolster end extending into said bolster opening with a widened top por-

tion in guiding engagement with said columns, an interlocking member associated with said bolster end and also interlocked with said columns, clamping means on said interlocking member outboard of said frame, and a control bar resiliently secured in said clamping means and having end portions connected to said columns.

5. In a four wheel truck, a truss side frame having top and bottom members and spaced columns defining a central bolster opening and spaced window openings, each of said columns having a transverse web and inboard and outboard flanges, a bolster end extending into said bolster opening with a widened top portion in guiding engagement with said columns, an interlocking member associated with said bolster end and also interlocked with said columns, clamping means on said interlocking member outboard of said frame, and a control bar secured at spaced points in said clamping means and having inturned end portions resiliently connected to said inboard flanges.

6. In a four wheel truck, a truss side frame having top and bottom members and spaced columns defining a central bolster opening and spaced window openings, each of said columns having a transverse web and inboard and outboard flanges, a bolster end extending into said bolster opening with a widened top portion in guiding engagement with said columns, an interlocking member associated with said bolster end and also interlocked with said columns, aligned clamping means on said interlocking member outboard said frame, and a control bar resiliently secured in said clamping means and extending into said window openings for connection to said inboard flanges.

7. In a railway car truck, a side frame having top and bottom members and spaced columns forming a central bolster opening, a bolster extending into said opening with widened portions in guiding engagement with said columns, an interlocking member associated with said bolster and having end portions in guiding engagement with said columns, said interlocking member having spaced clamping means outboard said frame, and a control bar resiliently connected in said clamping means, said control bar having inturned end portions resiliently connected to the inboard flanges of said columns.

8. In a railway car truck, a side frame having top and bottom members and spaced columns forming a central bolster opening, a bolster extending into said opening with widened portions in guiding engagement with said columns, an interlocking member associated with said bolster and having end portions in guiding engagement with said columns, said interlocking member having spaced clamping means outboard said frame, and a control bar resiliently connected in said clamping means and secured to said columns at spaced points.

9. In a car truck, a side frame having a central bolster opening with vertical columns at opposite sides thereof, a bolster extending into said opening with lateral portions in guiding engagement with said columns, an interlocking member associated with said bolster, clamping means on said interlocking member outboard said frame, and a control bar resiliently secured by said clamping means, said control bar having end portions inturned and connected to the inboard flanges of said columns respectively.

10. In a car truck, a side frame having a central bolster opening with vertical columns at opposite

sides thereof, a bolster extending into said opening with lateral portions in guiding engagement with said columns, an interlocking member associated with said bolster, clamping means on said interlocking member outboard said frame, and a control bar resiliently secured at spaced points by said clamping means, said control bar having inturned end portions resiliently connected to said columns respectively.

10. In a car truck, a side frame having a central bolster opening with vertical columns at opposite sides thereof, a bolster extending into said opening with lateral portions in guiding engagement with said columns, an interlocking member associated with said bolster, clamping means on said interlocking member outboard said frame, and a control bar resiliently secured in said clamping means, said control bar having inturned end portions resiliently connected to said columns respectively.

15. In a car truck, a side frame having a central bolster opening with vertical columns at opposite sides thereof, a bolster extending into said opening with lateral portions in guiding engagement with said columns, an interlocking member associated with said bolster, clamping means on said interlocking member outboard said frame, and a control bar resiliently secured at spaced points in said clamping means, said control bar having inturned end portions resiliently connected to said columns respectively.

20. In a railway car truck, a side frame having a bolster opening, vertical columns at opposite sides thereof, a bolster extending into said opening with lateral portions in guiding engagement with said columns, an interlocking member associated with said bolster, clamping means on said interlocking member, a tie bar resiliently secured at spaced points in said clamping means, and inturned end portions on said tie bar resiliently connected to said columns respectively.

25. In a car truck, a side frame having a bolster opening, vertical columns at opposite sides of said opening, a bolster extending into said opening, a bolster interlocking member having guiding engagement with said columns, clamping means on said member adjacent each column, and a control bar secured between said clamping means and having inturned end portions resiliently connected to the inboard flanges of said columns respectively.

30. In a railway car truck, a side frame having top and bottom members and spaced columns forming a central bolster opening, a bolster extending into said opening with widened portions in guiding engagement with said columns, an interlocking member having spaced clamping means outboard said frame, and a control bar resiliently connected at spaced points in said clamping means and having inturned end portions connected to said columns respectively.

35. In a car truck, a side frame having a bolster opening, vertical columns at opposite sides of said opening, a bolster extending into said opening, a bolster interlocking member having guiding engagement with said columns, clamping means on said member adjacent each column, and a control bar secured between said clamping means and having inturned end portions resiliently connected to the inboard flanges of said columns respectively.

40. In a railway car truck, a side frame having a bolster opening, vertical columns at opposite sides thereof, a bolster extending into said opening with lateral portions in guiding engagement with said columns, an interlocking member associated with said bolster, clamping means on said member and a tie bar secured in said clamping means and connected to said columns, said connection comprising resilient pads secured to said columns and to said tie bar.

45. In a car truck, a side frame having a bolster opening, vertical columns at opposite sides of said opening, a bolster extending into said opening, a bolster interlocking member having guiding engagement with said columns, aligned means on said member adjacent each column, and a control bar resiliently secured in said means and connected to said columns respectively.

50. In a railway car truck, a side frame having a bolster opening, vertical columns at opposite sides thereof, resilient means on said frame in said opening, a load bearing unit seated on said means and interlocked with said columns, said unit comprising a bolster and an interlocking member, clamping means on said unit, and a

tie bar resiliently secured in said clamping means and connected to said columns.

18. In a railway car truck, a side frame having a bolster opening, vertical columns at opposite sides thereof, a bolster member extending into said opening, a bolster interlocking member, clamping means on at least one of said members, and a tie bar resiliently secured in said clamping means and connected to said columns.

19. In a railway car truck, a side frame having a bolster opening, vertical columns at opposite sides thereof, resilient means on said frame in said opening, a unit transmitting load from an associated car body to said resilient means and comprising a bolster and an interlocking member, securing means on said unit, and a tie bar resiliently secured by said last-mentioned means and connected to said columns.

20. In a railway car truck, a side frame having a bolster opening, vertical columns at opposite sides thereof, resilient means on said frame in said opening, a load bearing unit seated on said means and interlocked with said columns, said unit comprising a bolster and an interlocking member, clamping means on said unit, and a tie bar secured in said clamping means and

having a connection at each end thereof to the associated column, said connection comprising resilient pads secured to said column and to said end.

21. In a railway car truck, a side frame having a bolster opening, vertical columns at opposite sides thereof, a bolster unit extending into said opening and comprising means interlocking said unit with said columns, clamping means on said unit, and a tie bar secured in said clamping means and resiliently connected to said columns, said connection comprising resilient means adapted to control lateral, longitudinal and vertical movements of said bolster unit.

22. In a railway car truck, a side frame having a bolster opening, vertical columns at opposite sides thereof, resilient means on said frame in said opening, a unit transmitting load from an associated car body to said resilient means and comprising a bolster and an interlocking member, securing means on said unit, and a tie bar secured by said last-mentioned means and connected at the ends thereof to said columns, said connection comprising resilient pads secured to said columns and to said ends.

ROBERT B. COTTRELL.
